UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

THERMIONIC VACUUM TUBE.

Application filed November 1, 1917. Serial No. 199,646.

To all whom it may concern:

Be it known that I, RAYMOND A. HEISING, a citizen of the United States, residing at East Orange, in the county of Essex and 5 State of New Jersey, have invented certain new and useful Improvements in Thermionic Vacuum Tubes, of which the following is a full, clear, concise, and exact description.

10 This invention relates to thermionic vacuum tubes of the type in which the source of electrons is a heated filament and relates in particular to an arrangement for heating the filaments of such tubes.

15 The object of this invention is to provide a method and means whereby a series arrangement of filaments of several thermionic vacuum tube devices may be heated to the same degree, using for this purpose a common source of current. This is accomplished

20 by means of resistances for shunting the filaments so that some current is shunted or bypassed around certain filaments which tend to overheat owing to the fact that they carry 25 the space current traveling to other filaments. An equal amount of energy is thus used in heating each filament. An arrangement is also contemplated in which the burning out of the filament of one tube will 30 not cause a filament of any other tube connected therewith to burn out.

In the accompanying drawings, Fig. 1 illustrates diagrammatically an arrangement for heating the filaments of three tubes in 35 series from a common source; and Fig. 2 illustrates an arrangement wherein four filaments are heated in a series parallel arrangement.

40 In Fig. 1 numerals 5, 5' and 5'' represent three vacuum tubes of the audion type. Between the terminals of the filament of tube 5 is a resistance 6 and between the terminals of the filament of tube 5' is a resistance 6'. Each filament and its associated resistance 45 forms a parallel combination which combinations are connected in series with each other, the filament of tube 5'', a battery A, and an adjustable resistance 7. Battery A is the heating battery. The plate circuits of 50 the vacuum tubes are connected at 8 through the output battery B to the terminal of resistance 6 remote from resistance 6'. The output circuit is illustrated as containing a coil of a transformer 9. The grid circuits

are omitted to simplify the drawings. The 55 batteries A and B have their negative terminals connected to point 8. If the resistances 6 and 6' were absent the filaments would all carry a certain heating current due to the voltage of A. The filament of 5 would also 60 carry the space current of tubes 5' and 5'' while the filament of 5' would carry the space current of tube 5''. The resistance 6 and 6' are so proportioned, however, that they shunt a certain current, around their 65 respective filaments. The resistance 6 being smaller, shunts a greater current than resistance 6' so that the filaments of all the tubes carry substantially the same current. The resistance 7 may be adjusted to regulate 70 the heating current. Three tubes have been illustrated but it is obvious that any desired number could be so arranged.

The arrangement of Fig. 2 is for heating the filaments 14, 15, 16 and 17 of vacuum 75 tubes 10, 11, 12, 13. Filaments 14 and 15 are in series with respect to a source of heating current C, filaments 16 and 17 are also in series therewith and these two series are in parallel with each other. The negative pole 80 of a generator D is connected through resistances 24, 25 to conductors 26, 27 which respectively connect filaments 14 and 15 and filaments 16 and 17. The other pole of D is connected to the plates of the various tubes 85 through a coil of a transformer 9 which symbolizes means for impressing the output of the thermionic vacuum tubes upon a circuit whereby said output may be utilized. The grid circuits of the various thermionic 90 tubes are omitted in order to avoid complicating the drawing. If the resistances 18 and 19 were absent the filaments 14 and 16 would receive more current than filaments 15 and 17 as would be seen by plotting the 95 current at all points between 20 and 21 and between 22 and 23.

Thus in passing along from resistance 20 toward resistance 21 and thus passing through filaments 14 and 15 in the same 100 direction, filament 14 would be found to have a rising current characteristic throughout its length and filament 15 to have a falling current characteristic throughout its length. The small arrows show how the currents from generators C and D are superimposed. However, the resistances 18 and 19 105 shunt a certain current around the filaments

14 and 16 so that the temperatures of the various filaments are equalized. In any such series of two or more filaments as 14 and 15 heated in series the unshunted member of the series may be considered as shunted by a resistance which is infinitely large as compared with the shunt resistance of the other members of the series.

The functions of resistances 20, 21, 22, 23, 10 24 and 25 will now be pointed out. Suppose all these resistances were absent from the arrangement of Fig. 2 then if filament 17 burned out, filament 15 would also burn out because it would be in series with both 15 of the filaments 14 and 16. The resistances 24 and 25, however, would cut down the current through filament 16 very much. The resistances 20, 21, 22, 23 are intended to further reduce this current in case a filament 20 burns out. It might at first glance appear that resistance 21 could advantageously be combined with resistance 20 and likewise resistance 23 with resistance 22 but if this were done and filament 17 burned out 25 then it would be seen that a greater current would pass through filament 15 if resistances 21 and 23 were combined with 20 and 22 respectively than if they were arranged as shown. In a particular instance a 50 volt 30 generator C was used with a 600 volt generator D; the filaments had resistances of approximately $2\frac{2}{3}$ ohms each; resistances 20, 21, 22, 23 were approximately 6 ohms each; while resistances 24 and 25 were about 40 35 ohms. Resistances 18 and 19 may be made adjustable to properly equalize the temperatures of the filaments. However, the invention is not limited to any particular relative or absolute values of the various voltages, 40 resistances or currents involved but values may be selected for these which are suitable to various operating conditions.

Although for purposes of illustration arrangements are shown wherein the outputs 45 of the vacuum tubes feed into a common transformer 9, this is not an essential part of the invention, but the several vacuum tubes may feed into independent circuits. It should be noted that the arrangement of 50 Fig. 2 is not limited to four vacuum tubes but a greater number can be placed in series with the heating generator and a greater number of such series combinations arranged in parallel or both. In case it is not 55 desired to guard against burning out of filaments the resistances 20, 21, 22, 23, 24 and 25 may be omitted, except that small resistances 20, 22 should be provided to effect adjustment of the heating currents of each 60 series.

What is claimed is:

1. In combination, a plurality of thermionic vacuum tubes, filaments therefor, said filaments being connected in series with 65 each other and a source of heating current,

the plates of said tubes being connected in parallel with each other, said parallel combination being connected with a source of space current, the opposite terminal of said source of space current being connected to 70 said filaments so that the space current when superimposed upon said heating current causes the amount of current flowing in one filament to be different from that flowing in another filament, and equalizing resistances across the terminals of certain of said filaments to shunt part of the current around said filaments.

2. In combination, a plurality of vacuum tubes having their filaments connected in 80 series with respect to heating current and in parallel with respect to space current whereby the space current of one of said tubes is superimposed on the heating current flowing through the filament of another of 85 said tubes, and a resistance path effectively in shunt to said last filament.

3. The method of energizing a plurality of vacuum tubes, which comprises passing heating current through their filaments in 90 series, passing space current through the tubes in parallel, thereby superimposing the space current of one of said tubes on the heating current flowing through the filament of another of said tubes, and by-passing a 95 portion of the current around said last filament.

4. A series of vacuum tubes having filaments in series with a source of heating current, said filaments being in parallel with a 100 source of space current, said second mentioned source being connected to said series so that the resultant currents of said sources through the several filaments tend to produce unequal heating of said filaments, and 105 shunting resistances associated with certain of said filaments in such a manner as to counteract said tendency.

5. A system of vacuum tubes in series parallel arrangement with respect to a 110 source of heating current, a terminal of a space current source connected to the middle point of each series, and resistances shunting the filaments of each series on one side of said middle point connection.

6. A system according to claim 5 having a resistance between each said middle point and said space current source.

7. In combination, a plurality of vacuum tubes, a generator of continuous difference 120 of electrical potential, a plurality of series circuits connecting the terminals of said generator, each circuit containing in the order named, a resistance, a plurality of vacuum tube filaments and a second resistance; a terminal of a second generator of difference of electrical potential connected between two of said filaments, the opposite terminal of said second generator being connected to electrodes of said tubes, and re- 125 130

sistances connecting the terminals of certain of said filaments for shunting them.

8. In combination, an electrical generator, a plurality of series circuits connecting the terminals of said generator, each circuit containing in the order named, a resistance, a plurality of vacuum tube filaments and a second resistance; a second generator having a terminal connected to each middle point of the several said circuits through respective resistances, the opposite terminal of said second generator being connected to said filaments by conducting means, and resistances connected between the terminals of said filaments so as to form shunts around said filaments.

9. A combination consisting of a source of electrical energy and a plurality of circuits supplied thereby, each circuit including a series of vacuum tube filaments, said filaments being in parallel with a source of space current, said second-mentioned source being connected to each of said series so that the resultant currents of said sources tend to produce unequal heating of said filaments, and shunting resistances associated with certain of said filaments in such a manner as to counteract said tendency.

10. A combination consisting of a source of electrical energy and a plurality of circuits supplied thereby, each circuit including a series of vacuum tube filaments adapted to be heated by the current from said source, means for unsymmetrically superimposing a space current upon the heating current of each series, and means for caus-

ing the heating effect of said combined currents to be substantially equal in the several filaments.

11. In a system of thermionic devices having filaments, the filaments of one group of said devices being connected in series, the filaments of another group of said devices being connected in series, a source of current for supplying heating current to said two series of filaments in parallel, and a connection bridged between the filaments of said groups intermediate the terminal devices of each group, said connection containing a resistance which is high compared with the resistance of each of said filaments.

12. In a system of thermionic devices having filaments and other electrodes, the filaments of one group of said devices being connected in series, the filaments of another group of said devices being connected in series, a source of current for supplying heating current to said two series of filaments in parallel, a connection bridged between the filaments of said groups intermediate the terminal devices of each group, said connection containing a resistance which is high compared with the resistance of each of said filaments, and a conductor extending from the midpoint of said bridged resistance to one of the other electrodes of a said device in each of said groups.

In witness whereof, I hereunto subscribe my name this 29th day of October, A. D. 1917.

RAYMOND A. HEISING.
